Primary Examiner — Robert M Spear*Assistant Examiner* — Rashida C McCoy(74) *Attorney, Agent, or Firm* — Gifford, Krass, Sprinkle, Anderson & Citkowski, P.C.; Douglas L. Wathen**CLAIM**

The ornamental design for a shoe, as shown and described.

DESCRIPTION

FIG. 1 is a perspective view of a shoe according to a first embodiment of the present invention;
 FIG. 2 is a perspective top view of the shoe of FIG. 1;
 FIG. 3 is a perspective side view of the shoe of FIGS. 1-2;
 FIG. 4 is a perspective bottom view of the shoe of FIGS. 1-3;
 FIG. 5 is a bottom opposite side view of the shoe of FIGS. 1-4;
 FIG. 6 is a rear perspective view of the shoe of FIGS. 1-5; and,
 FIG. 7 is a front perspective view of the shoe of FIGS. 1-6.
 The broken lines shown in the Figures are for environmental purposes only and form no part of the claimed design.
